UNITED STATES PATENT OFFICE.

LINTON T. BASSETT, OF CARTHAGE, MISSOURI

INTERNAL-COMBUSTION ENGINE.

1,271,833.

Specification of Letters Patent. Patented July 9, 1918.

Application filed July 10, 1916. Serial No. 108,337.

To all whom it may concern:

Be it known that I, LINTON T. BASSETT, a citizen of the United States of America, residing at Carthage, in the county of Jasper, and State of Missouri, have invented new and useful Improvements in Internal-Combustion Engines, of which the following is a specification.

This invention relates to the art of engines and particularly to an improved internal combustion engine.

One of the objects of the invention is to provide a multiple cylinder internal combustion engine of the gyroscopical type, for instance, a type in which the multiple cylinders are revoluble about a common axis, incident to the explosions in the combustion chambers of said cylinders, whereby, a more efficient uniform speed may be attained.

A further object of the invention is the production of a four-cycle multiple cylinder gyroscopical engine, having improved means for controlling the intake, the compression, the firing and the exhaust of the explosive charge, without the use of the types of valves heretofore used.

A further object of the invention is the provision of an engine of this kind, in which the pitman rods of the pistons are connected eccentrically to a stationary shaft, the engine casing having multiple cylinders attached thereto and revoluble concentric with said shaft and having pistons operable in said cylinders, incident to the explosions of the charges.

A further object of the invention is the provision of an engine of this kind having a revoluble engine casing with multiple cylinders having their pistons eccentrically connected to the engine shaft, and which casing is designed to make two-thirds of a revolution, while a charge controlling sleeve valve is making one-half of a revolution, whereby the admissions, compressions, firings, and exhausts of the charges are controlled.

In practical fields the details of construction may necessitate alterations falling within the scope of what is claimed.

The invention comprises further features and combinations of parts, as hereinafter set forth, shown in the drawings and claimed.

In the drawings:-

Figure 1 is a view in perspective of the improved multiple cylinder internal com-

bustion engine constructed in accordance with the invention.

Fig. 2 is a view in edge elevation of the engine.

Fig. 3 is a sectional view on line 3-3 of Fig. 1.

Fig. 4 is a sectional view on line 4-4 of Fig. 2.

Fig. 5 is a sectional view on line 5-5 of Fig. 3.

Fig. 6 is a sectional view similar to Fig. 5 but showing the cylinders eliminated and the sleeve valve and the engine sleeve in different positions.

Fig. 7 is a sectional view similar to Fig. 6 showing the sleeve of the engine casing and the sleeve valve in different positions.

Fig. 8 is a sectional view similar to Figs. 6 and 7 showing the engine casing sleeve and the sleeve valve in different positions.

Fig. 9 is a sectional view similar to Fig. 5, showing the sleeve valve and the engine casing in different positions to that shown in Fig. 5.

Fig. 10 is a sectional view similar to Figs. 5 and 9, but showing the sleeve valve and the engine casing in different positions to that shown in Figs. 5 and 9.

Referring more especially to the drawings, 1 designates a shaft, which is provided with a pair of passages 2 and 3 extending partially longitudinally through the shaft, the passage 2 acting as an intake, while the passage 3 may permit of the discharge of the exhaust. However, the intake may be allowed to pass through the passage 3, and the exhaust discharge out through the passage 2, when the engine is reversed. The inner ends of said passages 2 and 3 terminate in laterally extending substantially segment shaped ports 4 and 5. The inner end of the shaft 1 has connected to it integrally and eccentrically a disk 6, and projecting laterally from one face of said disk and eccentrically to the center of the shaft is a wrist pin 7. Mounted upon the shaft 1 (which is journaled in a bearing 8, which may be on a stationary frame or an automobile frame) is a hexagon shaped crank case 9. The wall 10 of said case has an opening 11 for the reception of the shaft 1, and the opposite wall of said case has an opening 12, through which access may be had to the interior of said crank case. Covering the opening 12 is a plate 13, which is secured by bolts 14 to said case. Extending from the plate 13 is a boss

15, which is arranged axially with the shaft 1, and connected integrally to the boss is a shaft 16. This shaft 16 is mounted in a bearing 17, which together with the bearing 8 5 may be carried by a stationary or automobile frame as indicated at 18. Any suitable means or the drive axle of an automobile (neither of which is shown) may be connected to the shaft 16, for imparting motion 10 thereto. Secured by suitable bolts 19 on three of the faces of the crank case are cylinders, designated respectively *a*, *b*, and *c*, each of which is provided with an explosion chamber 20. Operable in the chambers 20 15 are pistons 21, 22, and 23. Said pistons have pitman rods 24 connected thereto, the inner ends of which are in turn pivotally mounted at 25 on said wrist pin 7. Therefore, it is to be observed that when the crank case and its 20 cylinders are rotating, the pistons will reciprocate in the chambers 20. In other words, the cylinders being revoluble concentric to the shaft 1 and having the pistons connected eccentrically with relation to the 25 axis of the shaft 1, the pistons will move in said chambers 20, incident to the explosion of the charges, which charges may be fired by any suitable spark plugs (not shown). Projecting axially from the wall 10 of the crank 30 case is an extension sleeve 26, the inner circumference of which is spaced sufficiently from the shaft 1, as to permit of the reception of the sleeve valve 27. The sleeve valve is provided with diametrically oppositely 35 disposed elongated ports 28 and 29, which are designed to register with the ports 4 and 5, as the sleeve valve rotates. The extension sleeve 26 of the crank case is provided with ports 30, 31, and 32, which are designed at 40 various times to register with the ports 28 and 29, and 4 and 5, in order to control the charges. The sleeve valve is provided with an integral collar 33 provided with gear teeth 34, which may be engaged by any suitable 45 means, whereby the sleeve valve may be rotated exactly one-half of a revolution to two-thirds of a revolution of the crank case. Extending about the marginal edges of the ports 30, 31 and 32 are extension tubes 34, 50 in which the nipple couplings 35 are threaded. Tubes or pipes 36, 37 and 38 are threaded into the nipple couplings and have their outer ends in turn threaded into the lateral extensions 39 of the outer ends of the cylinders *a*, *b* and *c*. These extensions 39 have 55 passages 40, 41 and 42.

Referring to Figs. 5, 6, 7 and 8, the operation of the engine is as follows, with regard to the cylinder *a*. Assuming the cylinder *a* in Fig. 5 as beginning its admission stroke, by reason of the ports 28 and 30 being in registration, and the port 28 about to register with the port 4. The admission of a charge into the cylinder *a* is substantially 60 completed and the compression of said

charge is substantially beginning, when the cylinder *a* reaches a position substantially diametrically opposite to that shown in Fig. 5, as shown in Fig. 6. The following will occur, as the port 30 in Fig. 6 is almost 65 closed by the solid portion 45 of the valve sleeve 27. The compression of the charge continues, while the port 30 is moving over the solid part 45 of the valve sleeve until the cylinder *a* makes a half revolution from the 70 position shown in Fig. 6 to that shown in Fig. 7, the port 30 still being over the solid part 45 of the valve sleeve 27, and while the cylinder *a* is in such position the charge 75 is fired. The cylinder *a* continues on its working stroke from its position in Fig. 7 to that shown in Fig. 8, where the solid portion of the valve sleeve is about to uncover the port 30, in which case the cylinder *a* will begin to exhaust, since the port 30 is 80 starting to register with the port 29, which in turn is registering with the exhaust port 5. The cylinder *a* will continue to exhaust while the port 30 is moving over the port 29, until said cylinder *a* again reaches the 85 position shown in Fig. 5, and the port 29 is out of registration with the exhaust port 5, in which case the cylinder *a* will admit another charge, which will then be compressed, fired, and discharged as in the first 90 instance. In fact the cylinder *a* will make two complete revolutions to accomplish the admission of a charge. The cylinders *b* and *c* will likewise operate, as can be seen in 95 Figs. 5, 6, 7, 8, 9 and 10 clearly, and the cylinders *a*, *b* and *c* in functioning as above stated will have their ports 30, 31, and 32 alternately coöperating with the solid parts 45 and 46, and the ports 28 and 29 of the valve sleeve, to cover and uncover said ports 100 30, 31, and 32.

The invention having been set forth, what is claimed as new and useful is:—

1. In a multiple cylinder internal combustion engine, an engine shaft having longitudinally extending intake and exhaust passages provided with intake and exhaust ports at their inner ends, a crank case revoluble on said shaft and provided with radial cylinders, pistons operable in said cylinders 110 and having pitman rods eccentrically connected to said shaft, said crank case having an extension sleeve provided with ports having tubes of communication with the outer ends of the cylinders, a valve sleeve fitting 115 the shaft and extending into said extension sleeve and provided with ports, and adapted to be rotated at one-half of a revolution to two-thirds of a revolution of the crank case, whereby, the ports of the sleeve valve may 120 coöperate with the ports of the extension sleeve and said shaft.

2. In an internal combustion engine, a stationary shaft having longitudinally extending intake and exhaust passages having 130

their inner ends terminating in intake and exhaust ports, a crank case revoluble concentrically on said shaft and having multiple cylinders extending radially and provided 5 with an extension sleeve having three ports to alternately register with said intake and exhaust ports of said shaft, passages of communication between the ports of said extension sleeve and the outer ends of the 10 cylinders, whereby charges may enter the cylinders behind the pistons therein, to be compressed, fired and discharged, pistons operable in said cylinders and having eccentric connections with said shaft, and 15 means operable between the shaft and said extension sleeve for controlling the charges through said passages.

3. In an internal combustion engine of the kind set forth, a stationary cylindrical member, a revoluble engine case mounted thereon 20

and having multiple radial cylinders, pistons operable in said cylinders and provided with eccentric connections with said member, said member having an intake and an exhaust passage, means revoluble on the 25 member, and adapted to make one-half of a revolution to two-thirds of a revolution of the engine case, whereby each cylinder will admit a charge on the completion of every two complete revolutions, and means carried 30 by the cylinders coöperating with the last named means to permit the cylinders to admit and exhaust said charges.

In testimony whereof I affix my signature hereto in the presence of two witnesses.

LINTON T. BASSETT.
